UNITED STATES PATENT OFFICE.

HARRY S. HART, OF CHICAGO, ILLINOIS.

RAILWAY-CAR CONSTRUCTION.

1,398,512.

Specification of Letters Patent. Patented Nov. 29, 1921.

Application filed September 29, 1919. Serial No. 227,183.

To all whom it may concern:

Be it known that I, HARRY S. HART, a citizen of the United States, residing at Chicago, in the county of Cook and State of Illinois, have invented certain new and useful Improvements in a Railway-Car Construction, of which the following is a specification.

This invention relates to railway car construction.

As clearly set forth in some of my recent patents, for example, Patents Numbers 1,300,959, 1,300,960, 1,300,961, and 1,300,962, granted April 15, 1919, and Number 15 1,304,969, granted May 27, 1919, a great deal of importance is given to the question of increasing the carrying capacity of railway cars, and particularly dump cars. In the above-mentioned patents it will be seen that 20 the capacity of the cars has been increased greatly by changing the floor construction over the trucks.

In this present case it is my object to further increase the capacity of such cars, and 25 at the same time give added strength to the car sides, presenting a simple, neat and inexpensive construction adapted to meet the various requirements for successful commercial use.

30 These and other objects are accomplished by providing a car construction in which the car sides are spaced apart the maximum allowed amount, and at the ends thereof provided with a plurality of corrugations for 35 giving strength thereto, and providing ladder rungs adjacent the corrugations whereby said ladder is maintained substantially within the vertical confines of the car sides.

The invention is illustrated on the accompanying sheet of drawings, in which:

Figure 1 is a fragmentary side elevation of a railway car embodying my invention;

Fig. 2 is a sectional view taken in the plane of line 2—2 of Fig. 1;

45 Fig. 3 is a fragmentary sectional view taken in the plane of line 3—3 of Fig. 1; and Fig. 4 is a sectional view taken in the plane of line 4—4 of Fig. 3.

As is well known, the over-all dimensions 50 of railway cars must be within predetermined limits to meet all clearance conditions. To design a car in accordance with clearance conditions and at the same time increase the carrying capacity thereof an appreciable amount, is a problem to which 55 I have given considerable attention. As

mentioned above, the carrying capacity of cars has been increased greatly by improving the floor construction over the car trucks, it being assumed that the car sides were 60 spaced the maximum allowed distance. In cars now in use the ladders at the sides thereof extend outwardly from the car sides a considerable amount, thereby limiting, in accordance with clearance conditions, the 65 distance the car sides may be spaced. In this present case I have spaced the car sides an increased amount commensurate with the distance the ladders extend outwardly from each side of the car and have provided the 70 sides of the cars at the ends thereof with corrugations, adjacent to which ladder rungs are placed which lie substantially within the vertical confines of the side of the car, thereby increasing the carrying capacity of 75 the car and also increasing the strength of the sides of the car and at the same time presenting a ladder construction which is simple, neat in appearance, and relatively inexpensive.

80 Referring to the figures of the drawings, it will be noted that the car has sides 10, ends 11, and a floor 12, the car sides 10 substantially throughout their entire length being spaced apart the maximum allowed 85 amount. The car sides 10 at the ends thereof are provided with corrugations 13, the depth of which increases downwardly from a zero point 14 coincident with the side of the car to a point 15 of maximum depth, 90 from which the corrugation rapidly decreases to the next underlying zero point 14. Adjacent the deepest portions of the corrugations, ladder rungs 16 are provided which are secured to the car sides, and it will be 95 noted that these ladder rungs lie substantially within the vertical confines of the car sides. The upper ladder rung 17 extends outwardly a slightly greater distance to compensate for the relatively shallow corrugation 18 adjacent thereto. In climbing up or down the ladder, it is simply necessary for one to maintain the toe in constant contact with the corrugated portion and slide the foot downwardly, whereby the foot will 105 be guided in a manner to make the footing safest, the foot passing into the corrugations in accordance with the depth thereof. The lower ladder section 19 may be of the usual type and arranged in its usual manner. By providing the ends of the car sides with corrugated portions, it is not necessary 110

to offset the top member 20 of the car sides at the ladder portion thereof.

It is my intention to cover all modifications of the invention falling within the 5 spirit and scope of the following claims.

I claim:

1. A railway car having sides, ends and a floor, the sides being spaced apart the maximum amount to increase the carrying capacity of the car, said sides having a plurality of corrugations formed therein, and ladder rungs secured to the car sides opposite the depressed portions of said corrugations and extending lengthwise beyond the 15 ends of the corrugations.

2. A railway car having sides, ends and a floor, the sides being spaced apart the maximum amount to increase the carrying capacity of the car, said sides having a plurality 20 of corrugations the depth of which varies, and ladder rungs secured to the car sides adjacent the deepest portion of said corrugations.

3. A railway car having a body portion including a side with corrugations formed 25 therein, and ladder rungs secured to said car side adjacent the deepest portion of said corrugations.

4. A railway car having a body portion including a side with a plurality of tapering 30 corrugations formed therein, the corrugations increasing in depth from a point coincident with the outer surface of the car side, and ladder rungs secured to the car side adjacent the deepest portion of said 35 corrugations.

5. A railway car having a body portion, said body portion including a wall with corrugations formed therein and ladder rungs secured to said wall adjacent the ends of the 40 depressed portions of said corrugations and extending lengthwise thereof.

Signed at Chicago, Illinois, this 22nd day of September, 1919.

HARRY S. HART.
